UNITED STATES PATENT OFFICE.

OSWALD S. PULLIAM, OF PITTSBURGH, PENNSYLVANIA.

CAR-BODY-UNDERFRAME CONSTRUCTION.

1,172,732.

Specification of Letters Patent. Patented Feb. 22, 1916.

Application filed July 10, 1911. Serial No. 637,641.

To all whom it may concern:

Be it known that I, OSWALD S. PULLIAM, of Pittsburgh, in the county of Allegheny and State of Pennsylvania, have invented 5 certain new and useful Improvements in Car - Body - Underframe Constructions, of which the following is a specification.

In some types of car constructions it is highly desirable to employ continuous center-sills, that is to say, center-sills extending longitudinally from end to end of the car body underframe. In this type of construction, however, considerable trouble has heretofore been encountered due to buckling of 10 the center-sills between the respective body-bolsters and the respective end-sills of the underframe due to the strains to which these portions and the center-sills are subjected by the draft rigging. 15 An object of the present invention is to provide a new and improved car body underframe employing continuous center-sills in combination with means coacting with the draft rigging and body-bolster to relieve 20 those portions of the center-sills between the body-bolster and end-sill from the strains and shocks to which said portions are ordinarily subjected.

In the accompanying drawing, which 25 illustrates applications of my invention, Figure 1 is a plan of one end of a car body underframe constructed in accordance with my invention; Fig. 2, a longitudinal sectional view taken on line II—II of Fig. 1; Fig. 3, a cross sectional view taken on line III—III of Fig. 1; and Fig. 4, a plan of a modified form of construction.

Referring to the drawing, 2 designates the side-sills of the underframe, and 3, an end-sill thereof of the usual and well known construction.

The center-sills, designated by the number 4, are preferably of channel form and extend longitudinally of the car from one 45 end-sill to the other end-sill. As illustrated, the center-sills are provided with slots 5 adapted to receive the followers 6 and 7 of the draft rigging. In the form of Fig. 1, each of the center-sills is provided with a 50 follower stop 8, secured thereto by rivets or other suitable means.

In the construction of the body-bolster as illustrated, I have shown a two-part or divided body-bolster 9 having the parts secured to the center-sills in any suitable manner.

Located between the center-sills and between the two parts constituting the body-bolster, I provide a filler or diaphragm 10. Diaphragm 10 is preferably of the form shown, and comprises a hollow metallic structure designed to practically fill the space between the center-sills and to project forward from the bolster only to the rear follower 7 of the draft rigging. Diaphragm 10 is preferably formed with a bearing 11 and a king-pin opening 12, and in addition thereto, with a rear follower engaging member or members 13.

In the form of Fig. 4, the filler or diaphragm 10^a or a portion thereof extends forwardly for a greater distance than the filler or diaphragm 10 of the form of Fig. 1. In the second form the filler 10^a in addition to the rear follower engaging members 13^a, is provided with engaging members 14 adapted to engage the forward follower 6.

It is evident that my invention may be employed with a different construction of draft rigging than that shown, and that my invention will relieve the center-sills of the shocks and strains above mentioned whether employed in connection with the draft rigging illustrated or some other well known form.

What I claim is:

1. In a metallic car body under frame and in combination, an end sill, a metallic body bolster, metallic center sills extending through the body bolster to the end sill, and slotted to permit follower movements, draft rigging including a follower structure, and an integral metallic diaphragm having opposite faces in contact with and secured to the center sills in the plane of the bolster, said diaphragm projecting forwardly a distance less than the distance between the bolster and end sill, said diaphragm also including a follower-engaging member positioned relative to predetermined sill slots to prevent rigging strain under buffer pressure on the center sills intermediate the bolster and end sill.

2. In a metallic car body underframe and in combination, an end sill, a metallic body bolster, metallic center sills extending through the body bolster to the end sill and slotted to permit follower movements, draft rigging including a follower structure, and an integral metallic diaphragm having opposite faces in contact with and secured to the center sills in the plane of the bolster,

said diaphragm projecting forwardly of the body bolster a distance sufficient to provide a stop for the forward follower and insufficient to extend to the plane of the end sill,
5 said forwardly projecting portion being slotted in correspondence with the sill slots, and having follower engaging members positioned relative to the sill slots and adapted to form stops for follower movements,
10 said stops acting to prevent rigging strains

under pulling and buffing pressures on the center sills intermediate the bolster and end sill.

In testimony whereof I affix my signature in presence of two witnesses.

OSWALD S. PULLIAM.
